WITNESS:

William M. Cassedy, INVENTOR
BY *Victor J. Evans*
ATTORNEY

UNITED STATES PATENT OFFICE.

WILLIAM M. CASSEDY, OF CAPE MAY, NEW JERSEY.

TOOTHBRAHSH.

1,405,279.

Specification of Letters Patent. Patented Jan. 31, 1922.

Application filed December 4, 1920. Serial No. 428,351.

To all whom it may concern:

Be it known that I, WILLIAM M. CASSEDY, a citizen of the United States, residing at Cape May, in the county of Cape May and 5 State of New Jersey, have invented new and useful Improvements in Toothbrushes, of which the following is a specification.

This invention relates to a device to be substituted for the ordinary tooth brush, the 10 general object of the invention being to provide a device of this nature, so constructed that it can be used to gently massage the gums and other portions of the mouth by a combined pressure and suction action, thus 15 restoring diseased gums to a healthy condition, keeping healthy gums in normal condition and removing particles of food and other foreign matter from between the teeth and polishing the teeth. The device is also 20 constructed to retain the medicine, cleansing material or the like at its point of contact with the gums and teeth so that but a small quantity of the medicine or other material need be used and that all parts of the gums 25 and teeth will be subjected to the action of the medicine or other material.

Another object of the invention is to provide means for preventing a too severe vacuum from being created which might injure 30 the gums.

A still further object of the invention is to so form the parts that the cleaning parts will conform themselves to the parts of the mouth and teeth with which they are engaging 35 so as to thoroughly clean and massage the parts with which they are contacting.

A still further object of the invention is to so form the parts of the device that there is nothing to bruise or otherwise injure the 40 gums and to round all corners and edges to prevent the accumulation of foreign matter.

This invention also consists in certain other features of construction and in the combination and arrangement of the several 45 parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is an elevation of the invention.

Figure 2 is a plan view.

Figure 3 is a section on line 3—3 of Figure 1.

Figure 4 is a perspective view of a portion of the brush.

Figure 5 is a view showing the position 60 of the parts assume when brought into engagement with the teeth.

In these views 1 indicates the handle and 2 the head which are preferably formed of one piece of material, formed of any desired 65 material, such as the composition material from which tooth brushes are usually formed. In carrying out my invention I secure a block 3, preferably of spongy rubber, to the head 2 and to this block I secure 70 a strip 4, of harder material than that from which block 3 is made. This strip is formed with or has secured thereto the projections 5 which are of slightly tapered form, as shown in the drawings. Said projections 75 are spaced apart as shown and have cup-shaped depressions 6 formed in their outer ends, the edges around the depressions being rounded. Notches 7 are formed in said edges for preventing a too severe vacuum 80 action by the depressions.

It will be seen that the block 3 will act as a cushion and will permit the tapered projections to adjust themselves to fit that part of the mouth with which they are in contact, 85 thus permitting the edges around the cups to enter the spaces between the teeth to thoroughly clean the teeth and to engage the gums to produce a vacuum so that when the brush is moved a massaging action will be 90 set up thus improving the circulation of blood to the gums. The notches 7 will prevent the vacuum action being too strong, thus preventing injury to the gums or the pulling of the gums away from the teeth. 95

After the different portions of the brush are assembled they are vulcanized so as to make a unitary structure.

My brush can be made smaller than the ordinary bristle brush and is compact. All 100 the exposed surfaces are smoothed and the projections are rounded so that the brush is easily cleaned and there are no rough surfaces or the like to hold germs and foreign matter. The depressions in the projections 105 will hold the powder, paste or medicine being used and they will evenly distribute it upon the teeth and gums. Thus only a small quantity of the paste or medicine need be used as it is not wasted as in the ordinary 110

brushes. These cups will also force the medicine or paste into the spaces between the teeth and into the gums so as to get the full benefit therefrom. The formation of 5 the brush will provide a gentle action upon the gums and teeth which is much superior to the action of the harsh bristles of the ordinary tooth brush. My improved brush will thoroughly clean the mouth and at the 10 same time gently massaging the parts so as to increase the circulation, thus keeping the mouth in healthy condition and greatly benefitting diseased mouths.

The notches 7 also facilitate the deposition 15 of the cleaning material used as they insure the passage of said material or fluid from the depressions. Attention is called to the fact that the depressions hold the cleaning material or fluid just at the point where it is 20 needed.

If it is desired to form a vacuum the brush is pressed hard enough against the teeth and gums to close the notches 7 but if the vacuum is not desired the brush is pressed lightly 25 against the teeth and gums so as to not close said notches. When the brush is pressed upon an oval or an irregular shaped surface, such as a tooth, the walls of the depression in each projection are drawn together, rather 30 than be forced apart. When the brush is pressed against the teeth the projections will sink into the soft cushion 3 and they will be drawn together, rather than be forced apart, the projections assuming the position shown 35 in Figure 5.

In cleaning tarter from the teeth a powder containing abrasive material is used and with my brush this powder is held in the depressions and passes over the walls of the 40 depressions at the surface of the teeth just where it is needed.

It is thought from the foregoing description that the advantages and novel features of my invention will be readily apparent.

45 My device is especially useful in treating

diseased gums as the massaging action produced by the combined pressure and suction will remove the puss from the gums and at the same time increase the circulation of blood to the gums so that the gums are soon 50 restored to a healthy condition. Healthy gums are also kept in normal condition by this massaging action and particles of food and other foreign matter on the teeth and gums and between the teeth are quickly removed by my device.

I desire it to be understood that I may make changes in the construction and in the combination and arrangement of the several parts, provided that such changes fall within 60 the scope of the appended claims.

What I claim is:—

1. A device of the class described comprising a carrying member, a cushion of resilient material thereon, a plurality of projections on the cushion spaced apart and each formed of slightly resilient material with a shallow recess in its end forming a vacuum cup.

2. A device of the class described comprising a handle, a cushion of resilient material connected with the handle, a plurality of projections formed of material stiffer than that of the cushion, said projections being of slightly tapered shape with broad bases 75 and having shallow recesses in their ends providing vacuum cups, one wall of each recess having a notch therein.

3. A device of the class described comprising a handle, a cushion of spongy rubber connected therewith, a plurality of projections formed of flexible material connected with the cushion, said projections being of solid construction with shallow recesses in their ends and tapering outwardly, 85 the walls of the recesses having notches therein.

In testimony whereof I affix my signature.

WILLIAM M. CASSEDY.
